UNITED STATES PATENT OFFICE.

EDWARD P. DIETERLE, OF NEW YORK, N. Y., ASSIGNOR OF ONE-HALF TO ALBERT G. BARKER, OF NEW YORK, N. Y.

VIBRATORY TOOL.

Application filed June 8, 1921. Serial No. 476,058.

To all whom it may concern:

Be it known that I, EDWARD P. DIETERLE, a citizen of the United States, and resident of borough of Manhattan, in the city, 5 county, and State of New York, have invented certain new and useful Improvements in Vibratory Tools; of which the following is a specification.

This invention relates to vibratory tools 10 applicable for various purposes, and, by way of example, intended by me for use by jewellers in manipulating the settings for precious stones, etc.

In the art of setting jewels extreme delicacy of touch is requisite that the setting prongs, tines or sockets may have just the right degree of pressure applied in the proper direction in order that the fastening may be rendered both secure and symmetrical, whereby the jewel may be firmly held against displacement, and also that the appearance of the setting may have a pleasing and artistic effect. When the pressure of a setting tool is applied by manual means, as 20 is the present practice, the most skillful operator sometimes fails, either in according full security to the anchorage, or in attaining artistic symmetry therein. This is due to the fact that the hand applied pressure is 25 not susceptible of being exerted under complete control.

Therefore my invention consists in the provision of a tool which is capable, through mechanical means, of vibrating under the influence of a succession of internal impacts, that are created by a flying or free piston in response to alternately applied air pressure and suction forces.

This device consists of a hollow cylinder 40 having at one end means for fitting a setting tool thereto, and at its other end connecting with a flexible tube, whereby, with the aid of suitable pumping means, air pressure and suction are alternately applied to the hollow cylinder, in quick succession. The hollow cylinder contains a free piston which under an air pressure impulse is thrown against the tool engaging end of the cylinder, and under the succeeding suction impulse is drawn to the opposite end of the cylinder, where it meets a cushion to absorb the shock of its rearward movement, so that the vibratory shocks will be unidirectional, exerting force for impacting only in a forward direction relatively to the tool. Air

ports in the forward portion of the cylinder are provided to permit the reciprocatory action of the piston.

Other features and advantages of my invention will hereinafter appear;

In the drawing:

Figure 1 is a side elevation of a motor, a pump driven thereby, a vibratory tool, the latter shown in longitudinal section, a flexible tube operatively connecting said tool with said pump, and a rheostat, with control means, for regulating the speed of the motor, and

Fig. 2 is an end view of the motor, showing the means of connection between its rotor and the pump mechanism.

In carrying out my invention I provide a pump composed of a cylinder 1, having a plunger 2, said cylinder being here shown as attached to a motor 3 by a strap 4, and 75 said plunger having pivotal connection with a pitman 5, that connects with a crank 6, whose shaft 7, that is journalled in bearings 8, carries a gear 9, which is in mesh with a worm drive 10 mounted on the rotor 11 of 80 motor 3. The pump cylinder 1 has at its outer end a nozzle 12, adapted for engagement by a flexible tube 13, so that the plunger 2, in its inward strokes, may force air into tube 13, and so that said plunger, 85 in its outward strokes, may exert suction influence upon said tube.

The opposite end of tube 13 is adapted for connection with a threaded end nozzle portion 14 of a hollow cylinder 15, in which 90 is a free piston 16. Said cylinder 15, at its opposite end portion is interiorly threaded, as at 17, to receive the threaded portion 18 of a tool holder 19, said tool holder having a socket 20 for the reception of a tool 21, 95 which is to be secured in said holder as by means of a set screw 22.

The interior of cylinder 15 is exposed to the atmosphere, at its end near the tool holder, as by the ports 23, and, at its end 100 adjacent the nozzle portion 14, said cylinder is provided, interiorly, with a cushion which may be in the form of a helical spring 24.

In the operation of the motor, the plunger 105 2 will communicate a succession of alternate air pressure impulses and suction effects, through tube 13, to cylinder 15, the air pressure impulses acting upon the free piston 16, causing said piston to be projected 110

against the abutting end of tool holder 19, which comprises the tube closure at its forward end, thereby imparting a forward jar or shock to said cylinder and the tool 5 which is a rigid element thereof, and the reaction or suction strokes of the plunger 2 will draw back the piston into contact with the spring cushion 24, which latter will absorb the jar or shock that would otherwise be created by the piston in its reactive 10 movement.

Therefore, according to the speed with which the plunger is driven by the motor, and the consequent energy of the piston 15 operative impacts, so will the tool develop suitable vibratory force.

When used as a jeweller's setting tool, the tool 21 is grasped between the fingers and thumb of the operator's hand, and its point 20 is directed against the prong, tine or socket to be formed or shaped upon or about the jewel, whereupon the succession of forward impacts communicated to the device, in the reciprocatory action of the free piston 25 will permit the application of a regulated desirable degree of vibratory pressure.

Motor speed regulating means, here shown as a rheostat 25, actuated by foot control means 26, serves to vary the rate of rotor 30 revolution and thereby governs the rate of pump operation.

It will be appreciated that the herein de-

scribed device constitutes a manually directed tool, which permits it to be applied to the setting at those points where pressure is to be employed, but the artizan is not required to exert manual pressure in bending over the setting portions to bind them on the jewel, this part of the operation being mechanically performed by the 40 succession of impacts which create a vibratory action in the tool.

Therefore no tendency is present in the use of this tool to divert the direction in which the pressure is applied; and, furthermore, the setting operation may be performed more expeditiously with this mechanically actuated tool than with the usual 45 form of hand setting tool.

Variations within the spirit and scope of 50 my said invention are equally comprehended herein.

I claim:—

A pressure applying device to be manually held and directed comprising a hollow cylinder, a tool fixedly carried thereby, a free piston within said cylinder, and pneumatic means for reciprocating the piston throughout the cylinder extent to vibrate the device.

Signed at the borough of Manhattan, in 60 the city, county, and State of New York this 31st day of May, A. D. 1921.

EDWARD P. DIETERLE.
